UNITED STATES PATENT OFFICE.

JOHN F. SEIBERLING, OF AKRON, OHIO.

GRAIN-BINDER.

SPECIFICATION forming part of Letters Patent No. 399,703, dated March 19, 1889.

Application filed May 22, 1888. Serial No. 274,654. (No model.)

To all whom it may concern:

Be it known that I, JOHN F. SEIBERLING, of Akron, county of Summit, and State of Ohio, have invented a new and useful Improvement 5 in Grain-Binders, of which the following is a full, clear, and exact description, reference being had to the accompanying drawings, making part of this specification.

My invention relates to the means for compressing the grain to form the bundle and for tripping or setting the binder mechanism in motion to bind the grain; and it consists in certain details of construction and arrangement of parts, hereinafter fully described and claimed.

In the accompanying drawings, Figure 1 represents in rear elevation so much of a harvesting-machine as is necessary to show my improvement. Fig. 2 is a plan view of the cam-lever. Fig. 3 is a vertical section through the needle, needle-cam, cam-lever, switch, and compressor-arm. Fig. 4 is a side and an end view of the double switch detached. Fig. 5 is a rear elevation showing the position the 25 needle, cam-lever, &c., assume in discharging the bundle. Fig. 6 is a plan view of the needle, packing, and compressing mechanism, the binder-table being broken away to show said parts. Fig. 7 is a rear elevation of the binder-frame, table, and packers. Fig. 8 is a side elevation of the swiveling yoke connecting the compressor with the cam-lever. Figs. 9 and 10 are detail plan and front elevations, enlarged, showing the connections between the 35 crank-arm on the needle-shaft and its actuating and tripping devices; and Fig. 11 is a front elevation showing a modification in the construction of the connecting-rod between the needle-shaft and its actuating 40 crank-wheel and in the arrangement of the cam acting on said rod.

The machine to which my improvements are shown applied is of the class known as an "elevated binder," and the binder-frame consists of a longitudinal tubular rod or bar, A, the needle-shaft D, and sleeve B', in which said shaft is journaled, and connecting transverse bars C C'. The rod or bar A is journaled in the outer ends of brackets a, secured to the outer uprights of the elevator-frame near their upper ends, and the lower

end of the binder-frame is upheld by inclined standards a', secured at their lower ends to the machine-frame, and provided at their upper ends with half-sleeves, in which the needle-shaft and its sleeve rest, and which permit said end of the binder-frame to be raised and folded over against the elevator for transportation.

The sleeve B' referred to is an arm of the binder-gear standard B, which is of the well-known U shape, and in its other arm carries the knotted-actuating shaft, and from which the knotted breast-plate and knotted mechanism are suspended under any usual or preferred arrangement. The sleeve B' is provided on its lower side with laterally-projecting ears b b', to which the outer ends of the bars C C' are bolted. The needle-shaft D extends beyond the sleeve D' and the needle 65 D', which it carries, and supports a flanged sleeve, B³, having a laterally-projecting lug, b², to which the outer end of the binder-frame bar C² is bolted. The sleeve B³ has an outwardly-projecting flange or rib, b³, on its lower 70 side, to which a bar, C³, is bolted, and which extends rearwardly, forming a support for the outer edge of the binder-table at its rear end. The forward end of rib b³ is extended outward, forming an arm, b⁴, having a forwardly-projecting pin or spur, b⁵, on its outer end, forming a fixed pivot, on which the upper end of one of the swinging packer-links is pivoted. A similar arm, b⁶, on the rear end of the sleeve B', provided with a rearwardly-projecting spur, forms a like support for the other packer-link, as shown in Fig. 6.

The needle D' is fast on and vibrates with shaft D, and has on its heel end a cam, D². (Shown in rear elevation in Figs. 1 and 5 and 90 in vertical section in Fig. 3.) The cam has a thin vertical wall or web, d, forming its forward closed face or side, provided with a rearwardly-projecting peripheral flange, d', forming the outer wall of the cam proper. Within 95 the open shell thus formed is located what I term a "double switch," E, the form of which is shown in the detail views, Fig. 4, and around which a friction-roller, f, on a cam-lever, F, moves as the needle is vibrated, as will appear. This switch has a forwardly-projecting pivot, e, which is journaled in the wall d,

and has a socket in its lower face, in which rests the upper end of a small spiral spring, e' , which at its lower end rests on a ledge, d' , forming the upper wall of the cam-groove at 5 that point. The tension of spring e' is exerted to rock the outer end, e^2 , of the switch up against the sleeve proper of the needle or upper wall, d^3 , of the cam; but this tension is overcome twice in the movement of the roller 10 f around the switch—first, in passing the end e^2 , as the needle rises to pass the band to the knotter in moving outward over the switch, from the position shown in Fig. 1, and, secondly, in rising on the inner side of the switch 15 and passing the end e^3 thereof from the position shown in Fig. 5 to that shown in Fig. 1.

The cam-lever F is made in two parts, which permit the adjustment of the roller f to give it the proper working relation to the 20 cam and switch. The upper part, F', has a sleeve on its upper end, through which the lever is journaled to vibrate on the bar A, and the part F is slotted at its upper end and connected by a through-bolt, f' , with the 25 part F', to permit its adjustment for the purpose explained. The heel end of the cam D^2 has a projecting ledge or spur, d^4 , formed upon it, for a purpose that will appear.

G indicates the compressor, which is 30 adjustably secured to the outer end of an arm, G', which is pivoted at its inner end in the heel of the needle above the cam D^2 , as shown at g , Fig. 3. The cam-lever F is bifurcated, or has a branch, f^2 , near its outer end, between 35 which and the main body of the lever a yoke, H, is pivoted, said yoke being made in the rectangular form shown in Fig. 8, and provided with trunnions h , which form the pivotal connection with the lever F. The ends 40 of this yoke are perforated to receive a rod, h' , surrounded within the yoke by a spiral spring, h^2 , and threaded near the upper end of the yoke to receive nuts h^3 and h^4 , the first named for adjusting the tension of the spring h^2 , and the latter, h^4 , for limiting the upward 45 movement of the rod h .

The nut h^4 , if preferred, may be placed on the lower end of the rod h , below the yoke H, as shown in dotted lines, Fig. 8. The 50 upper end of the rod h' has a hook or pin, h^5 , formed upon it, which enters a slot, g' , formed in the compressor-supporting arm G'. The nut h^4 , as explained, limits the upward movement of the rod h' and the consequent length 55 of the yoke and rod between the trunnions and the pin h^5 , and the slot g' , in which the pin h^5 rests, allows a slight downward movement of the compressor-arm G' before it acts on the pin and rod to compress the spring h^2 .

60 The cam-lever F has an eye, f^3 , near its outer end, through which the lower end of a rod, I, passes, the upper end of said rod being pivoted to the arm G'. Near the upper end of rod I is a nut, i , and between said nut and 65 the lever F the rod I is surrounded by a spiral spring, i' , the tension of which is regulated by the adjustment of the nut i , and is

exerted to uphold the compressor against the pressure of the grain.

The arm G' is provided with a set screw or 70 bolt, g^2 , the pendent head or end of which rests on the ledge or spur d^4 on the cam or heel extension of the needle, said ledge forming by this arrangement a rigid support for or connection of the compressor-arm with the 75 needle in such manner that the first downward movement of the arm G' permitted by the slot g' before it acts on the cam-lever, and caused by the pressure of the grain on the compressor, causes said arm, acting through 80 the set-screw g^2 and ledge d^4 , to rock the needle-shaft slightly in its bearings for setting the binder mechanism in motion, as will appear.

The forward end of the needle-shaft D, or the end opposite that which carries the needle, 85 has a crank-arm, D^3 , fast on it, from which a connecting-rod, J, extends to a crank-pin, k , on the gear-wheel K on the knotter-actuating shaft for actuating the needle-shaft in the usual manner. The arm D^3 has a trip-arm, 90 D^4 , fast upon it, the outer upper end of which reaches within the path of an arm, L, formed on a pawl, l, pivoted to a pinion, L', on a driving-shaft, L², to engage a cross-head, L⁴, for actuating the pinion L', and thence, through 95 the usual train of gears, the gear-wheel K on the knotter-actuating shaft when said pawl is not held disengaged from shaft L², in a manner well understood.

To allow the slight rocking movement of 100 the needle-shaft above referred to, for throwing the arm D^4 up to release the pawl-arm L and throw the binder mechanism into action, it is necessary that the connecting-rod J shall yield slightly endwise. To permit this it is 105 made in two parts, viz: the rod J proper and a yoke, J', on its upper end in which the rod J can move slightly endwise, and which at its upper end is connected to the crank-pin k.

The lower end of the yoke J' is perforated 110 to receive the end of rod J, and the upper end of the latter, within the yoke, is screw-threaded to receive an elongated sleeve-nut, M, which, when the connecting-rod is drawn to its greatest length, abuts against the lower end wall 115 of the yoke, as shown in Fig. 9. A spring, j, surrounds the rod J between the yoke J' and a nut, j', adjustable on a threaded portion, j², of the rod for regulating the tension of the spring, which is exerted to hold the parts in 120 the position described. The spring j yields under the rocking movement of the needle-shaft described, and allows the rod to slide in the yoke, into the position shown in Fig. 10, sufficient to allow the arm D^4 to be rocked up 125 out of engagement with the pawl-arm and so to throw the binder-gearing into action.

The upper end of the sleeve-nut M is drawn down or reduced in diameter, and is screw-threaded internally to receive a set-screw, m, 130 provided with a jam-nut, m², for holding the screw at any desired adjustment. The head m' of the screw lies within the path of a cam, N', formed on a washer, N, fastened by a key

or pin, n , to the outer end of the crank-pin k , and which acts on the set-screw m to force the connecting-rod J outward just before the wheel K completes its revolution, and causing the arm D^4 to engage the pawl-arm L if from any cause the spring j should fail to act for that purpose.

In Fig. 11 the yoke is screwed on the rod J , and is adapted to slide on a crank-box, k' , on the crank-pin k , and the spring j is arranged within the yoke between the crank-box k' and an adjusting-nut, k^2 . In this construction the upper end of the yoke has a pin or spur on it, which is acted upon by a cam, N'' , on the face of the wheel K for forcing the pitman out to its full length.

The shaft L^2 , carrying the pinion L' and cross-head L^4 , serves also as the crank-shaft, actuating the packers, and constitutes the first or main binder gear-shaft.

The operation of the trip mechanism will be readily understood from the foregoing description.

The pressure of the grain against the compressor causes the depression of the compressor-arm, and the latter acts to rock the needle-shaft sufficiently to rock the arm D^4 up out of engagement with the pawl-arm L , thereby throwing the pinion L' into engagement with its shaft and setting the binder-actuating gearing in motion for binding the grain, after which the pressure on the compressor being removed, and the parts being returned to their former position, the arm D^4 again engages the arm L and throws the pinion out of engagement with its shaft until the pressure of the grain on the compressor causes the operation to be again repeated.

The folding leaf or hinged extension Q' of the binder-table Q , which acts as a cut-off to check loose straw and is in common use, in my invention is connected through an arm, q , and link q' with the outer swinging end of the cam-lever F . As the latter is depressed by the passage of the roller f under the switch E in the backward and downward movement of the needle, it serves to withdraw the compressor out of the way of the bundle and to depress the leaf Q' to the plane of the table Q , as shown in Fig. 5, to permit the discharge of the bundle in the usual well-known manner.

Having now described my invention, I claim as new—

1. The combination, with the needle and its shaft, of the cam rigidly secured thereto, the cam-lever pivoted on the frame, the yoke pivoted thereto, and the compressor connected to and supported by said yoke and also pivoted to the needle, substantially as described.

2. The combination of the needle-shaft, the

needle secured to said shaft, the cam secured to the heel end of the needle, the pivoted and adjustable cam-lever F , hinged at its upper end at or near the upper side of the binder-frame and supported at its lower end and actuated by a cam-roller on said lever engaging the cam on the needle, the compressor, and the pivoted and yielding connection between the cam-lever and compressor, substantially as described.

3. The combination of the needle-shaft, the needle secured to said shaft, the cam on the needle, the compressor-arm hinged to the needle below the shaft, the spur on the needle supporting the compressor in position to receive the grain, the compressor connected to said compressor-arm, the cam-lever, the hinged connection between the cam-lever and compressor-arm, permitting said arm to yield, the supporting-spring i' , and the spring-rod I , hinged to the compressor-arm and connected with the cam-lever F , in the manner substantially as described.

4. The combination of the yoke H , the spring h^2 in said yoke, the rod h' , provided with the hook or pin engaging the compressor-arm, the cam-lever F , hinged to the yoke, the compressor-arm G' , and the compressor G , substantially as described.

5. The combination, with the needle and the cam formed on the heel end thereof, and the compressor-arm connected to the heel of the needle, of the compressor-actuating lever F and yoke H , connecting said lever and compressor-arm and having the trunnions h , journaled in said lever, the rod h' , spring h^2 , and the adjustable nuts h^3 and h^4 on the rod h' , one to preserve the proper distance between the cam-lever and compressor-arm and the other to adjust the spring to its proper tension, substantially as described.

6. The combination, with the needle, the cam rigidly secured thereto, and the compressor, of the cam-lever carrying the cam-roller and made adjustable in length to preserve the cam-roller in proper relation to the cam, substantially as described.

7. The combination, with the needle, the adjustable compressor, and the compressor-arm connected with said needle, of the pivoted cam-lever F , the double switch E , and its spring e' , the yoke H , and connections interposed between said lever F and the compressor, and the cam-roller f on the cam-lever F , substantially as described.

In testimony whereof I have hereunto set my hand this 19th day of May, A. D. 1888.

JNO. F. SEIBERLING.
